UNITED STATES PATENT OFFICE.

EDWIN W. SEEGER, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROL SYSTEM FOR ELECTRIC ELEVATORS.

Application filed April 14, 1924. Serial No. 708,424.

This invention relates to control systems for electric elevators and the like.

In numerous elevator installations the traffic conditions are such that it is usually necessary to stop the car at every landing and the present invention has among its objects to provide an improved automatic controller for such installations.

Another object is to provide a controller for installations of the aforesaid character which provides for automatic stopping of the elevator car at every landing during ascent and descent thereof and which also provides for restarting of the elevator when the same is at any landing by opening and reclosure of the associated door or gate.

Another object is to provide an automatic controller of the aforesaid character including control means for preventing, when desired, automatic stopping of the elevator car at any of the landings.

Another object is to provide an automatic controller of the aforesaid character including control means for stopping the elevator car at any point between the several landings and other control means for effecting inching operations thereof in either direction.

Various other objects and advantages of the invention will hereinafter appear.

The accompanying drawing diagrammatically illustrates an embodiment of the invention and the same will now be described, it being understood that the embodiment illustrated is susceptible of modification without departing from the scope of the appended claims.

In the drawing,

Figure 1 is a diagrammatic view of the controller;

Fig. 2 is a so-called across the line diagram of the control means illustrated in Fig. 1.

Fig. 3 illustrates an operating mechanism for certain of the contacts shown in Fig. 1, and

Fig. 4 illustrates a modification of the controller shown in Fig. 1.

Referring to Fig. 1 the same illustrates an elevator car 1, a three-phase driving motor M therefor, and a pair of electromagnetic double pole reversing switches 2 and 3 for controlling the continuity of the line connections for such motor. Reversing switches 2 and 3 are controlled by relays 4 and 5 respectively, and for a purpose hereinafter set

forth each of said reversing switches is provided with normally open auxiliary contacts "a" and normally closed auxiliary contacts "b".

In addition to the foregoing more or less conventional elements, the controller includes an automatic floor selector, indicated generally at 6, which is operated by a shaft 7 driven at a reduced speed by the driving motor or otherwise operated in synchronism with the elevator car. The selector acts in conjunction with floor stop relays 8, 9, 10 and 11, one of said relays being provided for each landing, in the present instance, four. Also for purposes hereinafter set forth the controller includes a non-interference relay 12 having normally closed contacts 12^a and normally open contacts 12^b; switches DS¹ to DS⁴, inclusive, associated with the doors or gates at the several landings and control pushbuttons 13 to 16, inclusive, mounted in the elevator car, the pushbuttons 13, 14 and 16 being normally open and the pushbutton 15 being normally closed.

The floor selector 6 includes control devices 17 and 18, each of which is operated from shaft 7. Device 17 includes movable contacts 19 to 22, inclusive, one being provided for each landing and two groups of stationary contacts arranged on opposite sides of said movable contacts, one of said groups including contacts 20^a, 21^a and 22^a to cooperate with contacts 20, 21 and 22, respectively, and the other including contacts 19^b, 20^b and 21^b to cooperate with contacts 19, 20 and 21, respectively. Contacts 19 to 22 are operated from shaft 7 by a mechanism of the character shown in Fig. 3. As shown in the figure, each of the contacts 19 to 22 is mounted upon a pivoted supporting member "c" provided with a fork projection "d" and shaft 7 has a plurality of operating arms "e" fixed thereto, one being provided for actuating each of said members. The arrangement is such that when the elevator car is opposite any landing the movable contact of device 17 corresponding to such landing is held in an intermediate position by engagement of the operating arm "e" with the fork projection "d" of such contact. However, each of the movable contacts of device 17 is moved to one extreme position by its associated arm "e" and fork projection "d" when the elevator car is above its corresponding landing and to its

other extreme position by such parts when the elevator car is below its corresponding landing. Control device 18 includes a series of stationary contacts 23 to 28 inclusive and 5 a cooperating movable contact arm 29 which is operatively connected to shaft 7 through the medium of a lost motion connection including a pin 30 fixed to said contact arm and a member 31 fixed to said shaft. Member 10 31 is provided with spaced shoulders 32 and 33 for engaging opposite sides of said pin and the arrangement is such that when the elevator car is in one extreme position contact arm 29 occupies the position 15 shown in full lines while in the other extreme position of the elevator car said contact arm occupies the position shown in dotted lines. Assuming that the full line position of contact arm 29 corresponds to 20 the first floor position of the car, during movement of the car to the second landing the lost motion between shoulder 32 and pin 30 is taken up and upon arrival of the car at the second landing contact arm 29 engages 25 contact 24. Upon movement of the car to a position opposite the third landing contact arm 29 engages contact 26 and upon movement of the car to a position opposite the fourth landing contact arm 29 engages 30 contact 28. During downward movement of the car from the fourth landing the lost motion between shoulder 33 and pin 30 is taken up and when the car is opposite the third landing, contact arm 29 engages contact 35 27. Upon continued downward movement of the car, contact arm 29 engages contact 25 when the car is opposite the second landing and said arm returns to its full line position when the car reaches the 40 first landing.

The function and operation of the controller together with the circuit connections therefor will now be more fully described in connection with Fig. 2. Reversing switches 2 and 3 provide for establishment of reverse power connections for motor M from line L', L² and L³, such connections being apparent from Fig. 1, and it is assumed that reversing switch 2 provides for 45 upward operation of the elevator while reversing switch 3 provides for downward operation thereof. All of the control circuits extend from line L' through door switches DS¹ to DS⁴, inclusive and push button 50 15 to a conductor 35. Relays 4 and 5 serve to connect the operating windings of reversing switches 2 and 3, respectively, between conductor 35 and line L² and floor selector device 6 serves to establish a plurality of energizing circuits for relays 4 and 5 from conductor 35 to line L³, all of such circuits extending through the normally closed contacts 12^a of the non-interference relay 12. Each of the reversing switches in 55 closing insures against energization of the

control relay associated with the other reversing switch through opening of its auxiliary contacts 2^b or 3^b as the case may be and establishes an energizing circuit for the non-interference relay 12 between conductor 70 35 and line L² through the medium of its auxiliary contacts 2^a or 3^a as the case may be. In responding non-interference relay 12 maintains itself between conductor 35 and line L² through the medium of its auxiliary 75 contacts 12^b, and the same will remain in closed position pending opening of one of the door switches or the push button switch 15.

Assuming that the floor selector 6 is in 80 the position shown when the elevator car is at the first landing and that the same operates in the manner above described, it is apparent from the foregoing that if the door switch DS¹ has been opened contacts 12^a 85 of the non-interference relay 12 will be in closed position. Immediately upon closure of door switch DS¹ relays 4 and 9 respond, the operating windings thereof being connected between conductor 35 and line L' 90 through auxiliary contacts 3^b of reversing switch 3, contacts 20 and 20^a of control device 17, contact 23 and arm 29 of control device 18 and contacts 12^a of non-interference relay 12. Relay 9 in closing establishes 95 through its contacts 9^a a maintaining circuit for its operating winding and also the operating winding of relay 4 from conductor 35 to line L² through the auxiliary contacts 3^b of reversing switch 3 and contacts 20 and 100 20^a of control device 17, and relay 4 in closing effects response of reversing switch 2. Upon response of reversing switch 2 non-interference relay 12 responds and maintains itself as above set forth. Upon arrival 105 of the car at the second landing contact arm 29 engages contact 24 and contact 20 disengages contact 20^a to deenergize relays 4 and 9 for opening of reversing switch 2. The elevator car will then remain at the 110 second landing pending opening and reclosure of the door switch DS². Upon opening of door switch DS² the energizing circuit for non-interference relay 12 is interrupted and upon reclosure of said door 115 switch, relays 4 and 10 are energized through contacts 21 and 21^a of device 17 and contact 24 and arm 29 of device 18 and the former relay in responding maintains itself and also relay 4 in closed position through 120 closure of its contacts 10^a. Reversing switch then recloses for continued upward operation of the elevator car and the non-interference relay 12 responds and maintains itself through its contacts 12^b. Upon arrival 125 of the elevator car at the third landing contact arm 29 moves into engagement with contact 26 and contact 21 moves out of engagement with contact 21^a to deenergize relays 10 and 4 for opening of reversing 130

switch 2. The elevator car remains at the third landing pending opening and reclosure of the door switch DS³. Upon opening of the door switch DS³ the energizing circuit for relay 12 is interrupted and upon reclosure of said door switch relays 4 and 11 are energized through contacts 22 and 22^a of device 17 and contact 26 and arm 29 of device 18 and the latter relay in responding maintains itself and also relay 4 in closed position through closure of its contacts 11^a. Reversing switch 2 then recloses for movement of the elevator car to the fourth landing and the non-interference relay 12 again responds and maintains itself in closed position. Upon arrival of the elevator car at the fourth landing contact 22 disengages contact 22^a to deenergize relays 4 and 11 for opening of reversing switch 2 and upon opening 20 of the door switch DS⁴ non-interference relay 12 is deenergized.

When the elevator car is at the fourth landing the movable contacts of device 17 will occupy the positions shown in dotted lines and the contact arm 29 will also be in its dotted line position. Upon reclosure of door switch DS⁴ relays 5 and 10 are energized through the medium of contacts 21 and 21^b of device 17, and contact 28 and arm 29 of device 18 and the latter relay in responding maintains itself and also relay 5 in closed position through its contacts 10^a. Reversing switch 3 then closes for downward movement of the elevator car and the contacts 3^a thereof effect energization of non-interference relay 12. Upon arrival of the car at the third landing contact arm 29 moves into engagement with contact 27 while contact 21 disengages contact 21^b to deenergize relays 5 and 10 for opening of the reversing switch 3. The elevator car will then remain at the third landing pending opening and reclosure of the door switch DS³. Upon opening of the door switch DS³ the energizing circuit for non-interference relay 12 is interrupted and upon reclosure of said door switch relays 5 and 9 are energized through the medium of contacts 20 and 20^b of device 17, and arm 29 and contact 27 of device 18 and the latter relay in responding maintains itself and also relay 5 in closed position, through its contacts 9^a. Reversing switch 3 and non-interference relay 12 then respond and the elevator car moves downwardly to the second landing. Upon arrival of the elevator car at the second landing relays 5 and 9 are deenergized through disengagement of contacts 20 and 20^b and contact arm 29 moves into engagement with contact 25. Upon deenergization of relay 5 reversing switch 3 opens to stop the car at the second landing and the non-interference relay 12 maintains itself in closed position. Upon opening of the door switch DS² non-interference relay 12 is deenergized and upon reclosure thereof relays 5 and 8 are energized through the medium of contacts 19 and 19^b of device 17 and contact 25 and arm 29 of device 18. Relay 8 in responding maintains itself and also relay 5 in a closed position through its contacts 8^a and closure of the latter relay effects closure of reversing switch 3 which in turn effects closure of non-interference relay 12. When the elevator car arrives at the first landing reversing switch 3 is opened to stop the elevator through deenergization of relays 8 and 5 by disengagement of contacts 19 and 19^b. From the foregoing it is apparent that the aforescribed control means provides for automatic stopping of the elevator car at each landing both during ascent and descent thereof and also provides for restarting of the elevator car when the same is at any landing by opening and reclosure of the associated door or gate.

It is sometimes desired to prevent automatic stopping of the elevator car at a selected landing and for this purpose push button switch 16 is connected in shunt with the contacts 12^a of the non-interference relay 12. It is apparent that by maintaining such push button in closed position when the elevator car moves into a position opposite any of the landings the aforescribed energizing circuits for relays 4 and 5 will be established without opening and reclosure of the door switches. As before stated, all of the control circuits extend through push button 15 and it is thus apparent that when the elevator car is in any position between the various landings, opening of such push button will immediately interrupt the energizing circuits of the reversing switches to effect immediate stopping of the elevator. Furthermore, it should be noted that push button switches 13 and 14 are connected in shunt with operating windings of relays 4 and 5, respectively, whereby closure of push button switch 13 will effect energization of reversing switch 2 for upward movement of the elevator while closure of switch 14 will effect energization of reversing switch 3 for downward operation of the elevator. It is thus apparent that the push buttons 13 and 14 can be employed for inching purposes or for bringing the elevator from any position to a selected landing.

It is sometimes desirable to prevent automatic starting of the elevator car when the same is at any of its landings immediately upon reclosure of the associated door or gate. For this purpose a normally open push button 36, shown in Fig. 4, is mounted in the elevator car to be included in the circuit extending through the normally closed contacts 12^a of non-interference relay 12. As hereinbefore set forth the various energizing circuits established by the door switches for effecting response of relays

4 and 5, all extend through the normally closed contacts 12* of non-interference relay 12 and it is thus apparent that with the push button switch 36 arranged as shown in Fig. 5 4 it is necessary when the elevator car is at any landing to close the associated door switch and to also close said push button switch in order to start the elevator.

What I claim as new and desire to secure 10 by Letters Patent is:

1. In a controller for motor operated elevators, in combination, switches for establishing reverse power connections for the motor and control means therefor providing 15 for operation of the motor in opposite directions through a given range and for manual starting and automatic stopping thereof at predetermined points in such range, said means including a plurality of 20 manually operated switches, each for effecting starting of the motor at only one of said stopping points and means acting upon stopping of the motor at any of said points to necessitate given operations of the corresponding control switch as a prerequisite to 25 starting of the motor.

2. In a controller for motor operated elevators, in combination, switches for establishing reverse power connections for the 30 motor, a device to be driven in synchronism with the elevator car and means acting through said device to control said reversing switches for operation of the motor in opposite directions through a given range and 35 for manual starting and automatic stopping thereof at predetermined points in such range, said means including a plurality of manually operated control switches, each for effecting starting of the motor at only one 40 of said stopping points and means acting upon stopping of the motor at any of said points to necessitate given operations of the corresponding control switch as a prerequisite to 45 starting of the motor.

3. In a controller for motor operated elevators, in combination, a control device to be driven in synchronism with the elevator car, means acting through said device to provide for operation of said motor in opposite directions through a given range and for manual starting and automatic stopping thereof at given points in such range, said means including a plurality of manually operated control switches, each for effecting 50 starting of the motor at only one of said stopping points and means acting upon stopping of the motor at any of said points to necessitate opening and reclosure of the corresponding control switch as a prerequisite to 55 starting of the motor.

4. In a controller for motor operated elevators, in combination, means for effecting operation of the motor in opposite directions 60 through a given range and providing for manual starting and automatic stopping 65

thereof at predetermined points in such range, said means including a control device to be driven in synchronism with the elevator car, a plurality of manually operated control switches each to effect starting of said motor at only one of said points and a relay necessitating given operations of each of said control switches as a prerequisite to starting of said motor. 70

5. In a controller for motor operated elevators, in combination, switches for establishing reverse power connections for the motor, a device to be driven in synchronism with the elevator car, control means acting through said device to control said reversing switches for operation of said motor in opposite directions through a given range and for manual starting and automatic stopping thereof at given points in such range and means associated with said control means to prevent automatic stopping of said elevator at any of said points. 80

6. In a controller for motor operated elevators, in combination, switches for establishing reverse power connections for the motor, a device to be driven in synchronism with the elevator car, control means acting through said device to control said reversing switches for operation of said motor in opposite directions through a given range and for manual starting and automatic stopping thereof at given points in such range and means for stopping said motor at any point in said range and for restarting the same in either direction selectively. 90

7. In a controller for motor operated elevators, in combination, switches for establishing reverse power connections for the motor and control means for said switches providing for operation of said motor in opposite directions through a given range and also providing for manual starting and automatic stopping thereof at predetermined points in such range, said control means including a plurality of devices to be driven in synchronism with the elevator car, one of said devices being adapted to selectively establish a plurality of energizing circuits for said reversing switches through the other of said devices at said predetermined points and said latter device being adapted at said points to selectively interrupt the energizing circuits established therethrough by said former device. 100

8. In a controller for motor operated elevators, in combination, switches for establishing reverse power connections for the motor and control means for said switches providing for operation of the motor in opposite directions through a given range and for manual starting and automatic stopping thereof at predetermined points in such range, said control means including a plurality of devices to be driven in synchronism with the elevator car, one of said devices be- 110

ing adapted to selectively establish a plurality of energizing circuits for said reversing switches through the other of said devices at said predetermined points and said latter device being adapted at said points to selectively interrupt the energizing circuits established therethrough by said former de-

vice, and a non-interference relay for preventing completion of the energizing circuits for said reversing switches by said devices. 10

In witness whereof, I have hereunto subscribed my name.

EDWIN W. SEEGER.
